Des. 189,472

Patented Dec. 20, 1960

189,472

HARD SURFACE FLOOR COVERING OR SIMILAR ARTICLE

William Currie, Kearny, and Peter Zervas, Newark, N.J., assignors to Congoleum-Nairn Inc., Kearny, N.J., a corporation of New York

Filed Dec. 4, 1959, Ser. No. 58,551

Term of patent 7 years

(Cl. D92—17)

The figure is a plan view of a hard surface floor covering showing our new design.

A unit is enclosed within the broken lines on the drawing, which unit is repeated in regular succession as indicated by the extension beyond the unit boundaries.

We claim:

The ornamental design for a hard surface floor covering or similar article, substantially as shown and described.
